UNITED STATES PATENT OFFICE

JACOB C. STEDMAN, OF MEMPHIS, TENNESSEE

DESIGN FOR A LUNCH HOUSE

Application filed February 4, 1933. Serial No. 47,110. Term of patent 14 years.

To all whom it may concern:

Be it known that I, JACOB C. STEDMAN, a citizen of the United States, residing at Memphis, Shelby County, State of Tennessee, have invented a new, original, and ornamental Design for a Lunch House, of which the following is a specification, reference being had to the accompanying drawing, forming part thereof.

Fig. 1 is a perspective of a lunch house, the exterior being conventional, and

Fig. 2, a perspective of the interior of the same.

The dominant feature of my design consists of the interior construction shown in Fig. 2 and said feature includes the various lunchroom equipment shown, all of which consists of fixtures forming a permanent part of the lunchroom.

I claim:

The ornamental design for a lunch house as shown and described.

JACOB C. STEDMAN.
